(57) **CLAIM**

The ornamental design for a stabilizer for trolling motor, as shown and described.

DESCRIPTION

FIG. 1 is a front, right, and top perspective view of a stabilizer for a trolling motor showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, right, and top perspective view thereof showing the holding of a trolling motor shaft and the resting on a deck of a fishing boat; and,

FIG. 9 is a front, right, and top perspective thereof in an alternate position.

In the figures, the dashed broken lines depict portions of the stabilizer for a trolling motor that form no part of the claimed design. In FIG. 8, the dash-dot-dot-dash broken lines illustrate environmental structure and form no part of the claimed design.
